[57] CLAIM

I claim the ornamental design for a pessary extractor apparatus, as shown.

DESCRIPTION

FIG. 1 is a top, front, left perspective view of the pessary extractor apparatus;

FIG. 2 is a right side elevational view of the apparatus shown in FIG. 1.

FIG. 3 is a front elevational view of the apparatus shown in FIG. 1;

FIG. 4 is a rear elevational view of the apparatus shown in FIG. 1;

FIG. 5 is a top plan view of the apparatus shown in FIG. 1; and,

FIG. 6 is a bottom view of the apparatus shown in FIG. 1.
